UNITED STATES PATENT OFFICE.

CELESTIN F. NARDIN, OF WOODHAVEN, NEW YORK.

AUTOMATIC FIREARM.

1,067,054.

Specification of Letters Patent.

Patented July 8, 1913.

Application filed August 6, 1912. Serial No. 713,603.

To all whom it may concern:

Be it known that I, CELESTIN F. NARDIN, a citizen of France, residing at Woodhaven, Long Island, in the county of Queens and 5 State of New York, have invented new and useful Improvements in Automatic Firearms, of which the following is a specification.

The general object of the invention is to 10 improve the construction of automatic pistols by so arranging the several parts as to admit of their being readily dismantled whenever desired, and to obtain the full propelling effect on the projectile of the exploded gases. And to this end the invention 15 consists in certain combinations and arrangements of parts hereinafter more fully described and pointed out in the appended claims.

20 Other objects will appear and be better understood from that embodiment of my invention of which the following is a specification, reference being had to the accompanying drawings forming part hereof in 25 which:—

Figure 1 is a side elevation of the device. Fig. 2 is a detail side elevation of the movable side of the lock frame. Fig. 3 is a vertical longitudinal section taken through the 30 barrel, lock frame and upper portion of the magazine and showing the position of the parts at the end of the movement produced by the recoil. Fig. 4 is a detail partly in longitudinal section and side elevation showing 35 the position of the parts when the piece is loaded and preparatory to effecting the initial firing. Fig. 5 is a vertical cross section on the line 5—5 of Fig. 1. Fig. 6 is a detail side elevation partly in section of the 40 breech block and its lock. Fig. 7 is a detail side elevation of the trigger. Fig. 8 is a sectional plan view on the line 8—8 of Fig. 1. Fig. 9 is a sectional detail of the trigger lock. Fig. 10 is a section on the line 10—10 45 of Fig. 6 and also showing one side of the magazine.

The jacket or false barrel 5 interlocks with the lock frame 6 and for this purpose the lock frame and false barrel are by preference provided with mutilated threaded portions 50 7 which admit of effecting the interlocking of the parts when one of these, such as the false barrel, with the front sight hereof at right angles to the top of the lock frame, is inserted into the lock frame and given a quarter turn so as to bring the front

sight into alignment with the top of the lock frame.

The trigger frame 8 bears on a forwardly extending shelf 9 carried by the handle 10 and the trigger pin 11 which passes through the trigger 12 and through openings in the sides of the trigger frame 8, has one end loosely fitted in one side of the lock frame while its opposite end is loosely fitted in the opposite side 13 of the said lock frame, said opposite side 13 having one end pivoted to the under side of the false barrel 5 and its opposite end provided with a latch 14 which interlocks with the rear end of the lock frame 6 when the side 13 is arranged as shown in Fig. 1. By having the side 13 pivoted and acting as a door for the lock frame and at the same time as a means for co-operating with the opposite side of the lock frame to retain the trigger frame against lateral displacement, the said trigger frame together with the other parts in the lock frame, may be readily removed or inspected when the side or door 13 is swung outwardly.

The true barrel 16 is arranged in the false barrel 5 and is kept concentric with the said false barrel by a bushing 17 which it carries and which is of such size as to slide 85 within the false barrel 5. The retractor spring 18 has one end bearing on a sliding member 17' and its opposite end on a shoulder 19 in the false barrel 5.

The breech block 20 reciprocates in a longitudinal recess 21 in the upper side of the lock frame 6, its movements being limited by an end of the said recess 21 and the true barrel 16. The guides 22 carried by the breech block, slide in the guide grooves 23 in the forward end portion of the lock frame and are connected together at their outer ends as indicated at 24, at which point they are also pivotally connected to a handle 25 which latches onto a stud 26 depending from the forward end portion of the true barrel 16 and extending through a longitudinal slot 27 in the lower side of the false barrel 5. The rear end of the true barrel slides through the forward end of the lock frame 105 and this portion of the true barrel is somewhat enlarged and formed with an angular-shaped extension 28 and a cam groove 29. The cam groove 29 receives a stud 30 projecting inwardly from the lock frame and the angular-shaped extension 28 is adapted when turned, to interlock with an angular-

shaped recess 31 in the breech block 20. When the breech block and true barrel are interlocked the said true barrel forms a continuation of the breech block and the joint 5 between the parts is sufficiently tight to prevent any appreciable amount of gas escap- ing therethrough.

The sear 32 has one end pivoted in the hammer 33 and extends between the guides 22 of the breech block 20 and into longitudinal recesses 34 in the lower faces of said guides. The cam surfaces 35 at the forward ends of the recesses 34, depress the free end of the sear into detents 36 in the 10 sides of the trigger frame 8 when the breech block moves rearwardly and cocks the hammer 33. The trigger arm 37 is arranged so as to lift the sear from the detents when the trigger is pressed and the parts positioned as shown in Fig. 3, but when the sear 15 is first depressed into the detents and the breech block is in open position, the free end of the sear will be below and contacting with the under sides 4 of the guides 22, so that the lifting of the sear cannot be effected until the breech block moves forwardly and carries the cam surfaces 35 beyond the free end of the sear, at which time, of course, the breech block will be interlocked 20 with the barrel. Thus it will be seen that with this structure, the firing of the piece will be positively prevented until the breech block is closed.

The magazine 38 passes upwardly 25 through the hollow handle 10, the lock frame 6, through the sear 32 between the guides 22 of the breech block 20, and into alignment with the breech opening 39 in the upper side of the lock frame 6. The 30 upper end portions of the side walls of the magazine are inturned so as to prevent the cartridges from moving vertically upward when the breech block is opened, and to hold the uppermost cartridge in the path 35 of movement of the breech block when the latter moves forwardly. The magazine follower 40 is supported by the magazine spring 41 which lifts the follower with its load each time a cartridge is slid from the 40 upper end of the magazine. The follower moves in the path of a projecting portion 43 which extends through a longitudinal slot in the magazine, this projecting portion is carried by the safety 44, and coöper- 45 ates with the follower to lift the said safety into a notch 45 in the lower side of one of the guides 22 of the breech block 20. This action on the part of the follower, of course, takes place after the last cartridge in the 50 magazine has been fired and ejected and as the breech block is moving into the open position to effect the cocking of the hammer, so that the trigger may not be pulled until the safety is released and a filled mag- 55 azine substituted for the empty one.

The lower end of the magazine is provided on its opposite sides with push buttons 46 which have shank portions constructed so as to interlock with key hole slots in the opposite lower portions of the 60 handle 10.

In use and with the magazine filled with cartridges and with the parts positioned as shown in Fig. 3, the cocking of the piece is effected by simply pressing the trigger 75 12. Referring now to Fig. 3, it will be observed that there is associated with the trigger and its frame, a cocking lever 48 arranged in a recess in the trigger 12 and mounted on a pin 49 which passes through 80 the sides of the trigger frame. A stud 50 carried by the cocking lever 48, has its ends positioned in cam grooves 51 in the opposite sides of the recess of the trigger. A spring 52 arranged in a socket in the trigger 85 12, has one end bearing on a projection of the cocking lever so as to hold the said lever normally in the position shown in Figs. 3 and 4, so that when the trigger is 90 pressed, as before stated, a projection 53 of the cocking lever which bears on one end of the sear 32, when the parts are positioned as shown in Fig. 4, presses the said sear rearwardly until the end thereof enters the 95 detent 36 in the trigger frame. It will be observed that this movement on the part of the cocking lever is effected by the sides of the cam grooves 51 sliding on the stud 50. With the hammer cocked as shown in Fig. 100 3, further pressure on the trigger releases the sear and the hammer is moved forwardly under the action of its spring 54. It will be observed that during the action of cocking the hammer by the cocking lever 48, the breech block will remain stationary 105 and when the trigger is pressed so as to trip the sear, the projection 53 will have been turned forwardly and downwardly and out of the path of the sear 32. When the trigger is released the cocking lever will 110 be restored by its spring to the position shown in Figs. 3 and 4. Now, if we assume that the magazine is filled with cartridges and a cartridge arranged in position to be fired, at the initial cocking of the 115 hammer, then when the said hammer moves forwardly it will strike the firing pin 55 carried by the breech block 20 and this will effect the firing of the first cartridge. The recoil resulting from the firing of the first cartridge will move the breech block 20 rearwardly, and since this is interlocked with the true barrel the latter will also move rearwardly in unison with the breech block.

To assist the rearward movement of the parts, a spring pressed plunger 56 is provided and has one end abutting a shoulder on the enlarged portion of the true barrel 16. When the breech block and true barrel are 120 130

interlocked as shown in Fig. 4, the plunger spring will be compressed so as to expand when the breech block moves rearwardly under recoil, as before stated. During the rearward movement of the true barrel and breech block, the said true barrel is turned by the action of the stud 30 in the cam groove 29 and this turning of the true barrel effects the unlocking thereof from the breech block 20 by turning the angular-shaped projection 28 out of the recess 31. By this time the spring of the plunger 56 will have been fully expanded so that the true barrel will come to a stop, but the breech block will continue its rearward movement under the action of the recoil and thus effect the cocking of the hammer 33. With the hammer cocked, the breech block will move rearwardly until it abuts the rear end of the lock frame, whereupon the breech opening 39 will be opened so as to admit of the expulsion of the exploded cartridge by the combined retractor and ejector spring 57, which is arranged and constructed so as to fit in the groove of the cartridge when the same is within the true barrel 16 and be tensioned thereby. As the breech block moves rearwardly the retractor spring 18 is compressed so that when the force of the recoil is spent, the breech block will move to closed position under the action of the spring and during such movement will slide the uppermost cartridge from the magazine and direct the said cartridge into the true barrel 16. During the positioning of the cartridge in the true barrel the breech block will abut the rear end of the said true barrel and as the said breech block continues its forward movement the true barrel will be turned and moved longitudinally as to effect its interlocking with the breech block by the time that the latter is at the end of its forward movement, at which time the enlarged portion of the true barrel will abut against the shoulder presented by the inner end of the false barrel. Now with the hammer cocked by the recoil a slight pressure on the trigger is all that is necessary to effect the tripping of the sear and as the said sear moves forwardly, it will abut the projection 53 of the cocking lever and thus effect the projection of the trigger 12 against the pressure thereon by the operator's fingers. Now with the trigger projected, the detent 36 will be free to receive the sear when the latter is again move rearwardly under the recoil action on the breech block, thus the accidental firing of a second cartridge will be prevented.

What is claimed as new is:

1. In a recoil operated automatic pistol, 60 the combination with a lock frame, a trigger and a sear arranged in the lock frame; of a trigger frame arranged in the lock frame and adapted to interlock with the sear, and a cocking lever arranged to be operated by 65 pressing on the trigger to effect the interlocking of the sear with the trigger frame.
2. In a recoil operated automatic pistol the combination with a lock frame, a trigger and a sear arranged in the lock frame; of a 70 portion having a detent to receive the sear upon the cocking of the hammer, and a cocking lever associated with the trigger and operated thereby to effect the interlocking of the sear with the detent.
3. In a recoil operated automatic pistol, 75 the combination with a lock frame and a hammer arranged in the lock frame; of a sear pivotally connected to the hammer, a trigger located in the lock frame, a portion 80 arranged in the lock frame and having a detent to interlock with the sear when the hammer is cocked, and a cocking lever associated with the trigger and arranged to be operated by pressing on the trigger to effect 85 the interlocking of the sear with the detent.
4. In a recoil operated automatic pistol the combination of a lock frame, a slotted false barrel connected to one end of the lock frame, a true barrel slidably fitted in the 90 false barrel, a member slidably fitted on the true barrel and having a portion extending through the slot of the false barrel, a reciprocating breech block located in the lock frame, a handle member connected to the 95 breech block and adapted to latch onto the projecting portion of the sliding member.
5. In a recoil operated automatic pistol, the combination of a lock frame open on one side, a plate hingedly connected to one end 100 of the lock frame, and adapted to form a closure for the open side of the frame, means for locking the free end of the plate to the lock frame, a trigger frame arranged in the lock frame, and a trigger bar having a bearing in the said plate.

In testimony whereof I affix my signature in presence of two witnesses.

CELESTIN F. NARDIN.
